UNITED STATES PATENT OFFICE.

CURTIS A. NOBIS, OF BARRY, ILLINOIS, ASSIGNOR OF FOUR-FIFTHS TO OLIVER K. GARRETT, JOHN I. PARKER, HANNIBAL JONES, AND CHARLES BEARD, ALL OF BARRY, ILLINOIS.

WATER-POWER PLANT.

963,241.

Specification of Letters Patent.

Patented July 5, 1910.

Application filed July 14, 1909. Serial No. 507,602.

To all whom it may concern:

Be it known that I, CURTIS A. NOBIS, a citizen of the United States, residing at Barry, in the county of Pike and State of Illinois, have invented certain new and useful Improvements in Water-Power Plants, of which the following is a specification, reference being had to the accompanying drawings.

10 This invention relates to improvements in water power plants and more particularly one having one or more water wheels arranged below the low water mark in a flowing stream or river.

15 The objects of the invention are to provide a water power plant of this character which will be simple and practical; which has improved feathering blade wheels and improved means for directing and controlling the flow of water against the wheels.

With the above and other objects in view, the invention consists of the novel features of construction and the combination and arrangement of parts hereinafter fully described and claimed, and illustrated in the accompanying drawings, in which—

Figure 1 is a vertical longitudinal section through a construction embodying the invention; Fig. 2 is a vertical transverse section; Fig. 3 is a horizontal section taken on the plane indicated by the line 3—3 in Fig. 1; and Fig. 4 is a detail vertical section taken on the plane indicated by the line 4—4 in Fig. 3.

35 In the drawings 1 and 2 denote vertical walls arranged in a stream or river and extending longitudinally or in the direction of the flow of the current so as to provide between them a passageway 3 in which one or 40 more water wheels 4 may be arranged. The wheels 4 are disposed horizontally on vertical shafts 5 journaled in step bearings 6 at the bottom of the passageway 3 and also in suitable bearings 7 hereinafter described.

45 Each of the step bearings 6 is preferably provided with a packing box 8 to exclude sand and dirt therefrom and it is supplied with oil by means of an oil supply tube 9 arranged alongside of the shaft 5. Each of 50 the wheels 4 consists of a sleeve-like hub 10 suitably fixed upon the lower portion of the shaft 5 and provided with integral attaching lugs 11 to which are secured the inner ends of a plurality of radially extending 55 spokes or arms 12. Two annular sets or

series of the latter are provided and, while any number of them may be arranged in each set, I have shown in the drawings but four in each set. The outer portions of these spokes 12 have pivotally connected to them feathering blades or paddles 13, preferably three of the latter being provided on each spoke. The blades 13 are vertically disposed and extend across the spokes 12 of both the upper and lower series and they 60 are hinged or pivoted along one vertical edge to said superposed spokes 12 by providing upon their inner edges pivot lugs 14 which receive vertical pivot rods 14^a uniting the superposed spokes, as shown more 65 clearly in Fig. 1. By arranging these pivot or hinge connections at a suitable distance from the top and bottom edges of the blades, the latter will be limited in their swinging movement by their contact with the arms 12, 70 which latter are preferably bowed or curved longitudinally so that when the blades swing against them the blades will form a scoop-like pocket to receive the water and increase 75 the efficiency of the wheel.

If desired, a suitable housing 15 may be arranged upon the walls 12 and above the high water mark, the floor 16 of such housing supporting the bearings 7 for the shafts 5. When two of the wheels 4 are arranged 80 in the passageway 3, they are adapted to rotate in opposite directions and are, therefore, connected by suitable gearing 17 to a line shaft 18. It will be noted that by arranging and connecting up the wheels 4 in 85 this manner, the flow of the water through the passageway 3 will, on one side of said passage, pass through the feathered blades of the first wheel and strike the pockets formed by the folded blades of the second wheel and, likewise, the water on the other side of the passageway in leaving the pockets formed by the folded blades of the first wheel will have free passage through the feathered blades of the second wheel.

For the purpose of preventing drift wood and other trash from entering the passageway 3, the wall 1 is preferably made to extend a greater distance up stream than the wall 2 and a grating 19 is arranged diagonally across the front end of the passageway between said walls. This grating preferably consists of a vertical series of horizontally disposed slats or bars spaced a suitable distance apart, as shown in Fig. 1. If 110

desired, one or both of the walls may be flared outwardly at their front ends, as shown at 20, so as to direct water of the stream or river into the passageway and, if desired, in one or both of said walls may be formed openings 21 adjacent which are inclined wings 22 to direct the water into the passageway and against the wheels.

23 and 24 denote similar gates arranged 10 at the front and rear ends of the passageway 3 and mounted for vertical sliding movement between guides 25 on said walls. Hollow air tight boxes 26 are bolted or otherwise secured to the outer side faces of 15 the gates 23, 24 to form floats; and in order to guide these boxes or floats they are provided on their outer faces with oppositely projecting guide arms 26^a which slidably engage grooved guide bars 27 secured on the 20 opposite walls 1, 2 in parallel relation with the guides 25, which latter are also in the form of longitudinally grooved bars secured at opposite points on the inner faces of the upright walls. The gates 23, 24 are in the 25 form of rectangular plates the side edges of which engage the grooved guide bars 25. For the purpose of raising the gates 23, 24 out of the water, they are provided with vertically extending rack bars 28 which 30 mesh with cog wheels or gears 29 on a transverse shaft 30 mounted in suitable bearings in the housing 15. The shafts 30 are preferably provided with worm gears 31 which mesh with worms 32 on shafts 33 having 35 hand cranks 34. The gears 31 are keyed to

the shafts 30 so that they may be shifted into and out of mesh with the worms 32. The opening or openings 21 in the walls 1, 2 are preferably provided with gates 35 which are similar in construction and operation to the gates 23, 24.

Having thus described the invention what is claimed is:

The combination of a pair of vertical walls forming a passageway for a moving 45 body of water, a water wheel arranged in said passageway, a vertically movable gate arranged transversely in said passageway and consisting of a rectangular plate, longitudinally grooved guide bars secured at opposite points to the inner faces of said walls and adapted to receive the side edges of said plate forming a gate, a hollow air tight box fastened to one side face of the gate and forming a float for the gate, longitudinally 50 grooved guide bars secured at opposite points to the inner faces of said walls disposed in upright position and in parallel relation with respect to the first mentioned guide bars, oppositely projecting guide arms 55 on the outer side of the box or float and slidably arranged in the grooves of the second mentioned guide bars and means for manually raising and lowering the gate.

In testimony whereof I hereunto affix my 65 signature in the presence of two witnesses.

CURTIS A. NOBIS.
